UNITED STATES PATENT OFFICE.

ADOLPH KNOSHER, OF NAPERVILLE, ILLINOIS, ASSIGNOR, BY MESNE ASSIGNMENTS,
TO KODAV COMPANY, OF EAST CLEVELAND, OHIO, A CORPORATION OF OHIO.

FOLDING BED-LOUNGE.

1,157,700.

Specification of Letters Patent.

Patented Oct. 26, 1915.

Application filed February 18, 1914. Serial No. 819,349.

To all whom it may concern:

Be it known that I, ADOLPH KNOSHER, a citizen of the United States, residing at Naperville, in the county of DuPage and 5 State of Illinois, have invented new and useful Improvements in Folding Bed-Lounges, of which the following is a specification, reference being had to the accompanying drawings, forming a part thereof.

10 The purpose of this invention is to provide an improved construction of folding bed lounge with particular reference to improving the facilities for storage of bedding in the structure when folded up for use as 15 a lounge.

It consists in the elements and features of construction shown and described as indicated in the claims.

In the drawings: Figure 1 is a vertical fore-and-aft section of a folding bed lounge constructed according to this invention, the parts being in position for use as a lounge. Fig. 2 is a view similar to Fig. 1, showing the parts extended for use as a bed and the 25 lounge back folded up to position for uncovering the bedding receptacle in the back. Fig. 3 is a detail section of a back-supporting and latching device, the parts being shown in the position for engagement to support the up-folded back. Fig. 4 is a 30 view similar to Fig. 3, showing the parts in releasing position. Fig. 5 is a longitudinal horizontal section through the back frame, the back being broken away except at a small 35 portion where a hinge is shown. Fig. 6 is a detail view of the latch and latch-releasing device for engaging the seat at closed position.

The general structure of the folding bed 40 lounge shown in the drawings is in certain respects familiar, comprising a lounge frame consisting of lounge ends, 1, suitably connected by longitudinal members, of which there are shown the bottom front and rear 45 rails, 2 and 3, and the top rear rail, 4, of which the upper board, 8^a, of the box, 8, hereinafter described, may be regarded as a part. In this lounge frame there are mounted the members of the folding bed 50 frame, comprising a member, 5, which is hinged at its forward edge to the forward side of the lounge frame ends, and which constitutes a lounge seat supporting member, the lounge seat, 6, being mounted upon

its upper side at the position shown in Fig. 55 1, said member, 5, being adapted to swing up from lounge-seat-supporting position forward and downward to bed-supporting position, as seen in Fig. 2. The remainder of the folding-bed frame consists, as shown, 60 of a second member, 7, hinged to the member, 5, for folding down under said member, 5, at lounge-seat-supporting position of the latter. The construction, as thus far described, is familiar, resulting in the folding 65 under the lounge seat of all parts of the folding-bed frame, making it possible to have unobstructed space at the back of the lounge.

The features of this invention comprise a 70 box, 8, fixedly mounted in the back of the lounge frame forwardly open above the level of the lounge seat, and closed at its forward side by the lounge back, 9, which is hinged at its upper side to the forward edge 75 of the upper board, 8^a, of the box, 8, for swinging upward from operative position, shown in Fig. 1, to uncover the cavity of the box. Said box comprises vertical fore-and-aft members, 8^b, 8^b, which constitute the ends 80 of the box, and 8^c, 8^c, which are vertically positioned intermediate the ends, all of said members, 8^b and 8^c, having their forward edges sloped at a suitable angle to stop and support the lounge back, 9, at its operative 85 position. Upon one of said vertically extending fore-and-aft members of the box, 8, preferably upon one of the partition members, 8^c, and, for the purpose of protecting it from the contents of the box, preferably 90 between the two closely positioned members, 8^c, there is mounted a bracket, 10, which is engaged by a latch member, 11, hinged to the back side of the lounge back, 9. Said latch member has a stud, 11^a, which runs in 95 a slot, 10^a, of the bracket, 10, said slot being vertical through the greater part of its extent, but at the upper end, comprising a forwardly and slightly upwardly trending portion, 10^c, in the lower edge of which there is 100 a notch, 10^d, for engagement of the stud, 11^a, when the lounge-back, 9, is swung up to a position for uncovering the box, and adapted thereby to support the said lounge-back at that position.

The latch becomes engaged automatically by gravity as the lounge-back is swung up, and to facilitate the releasing of the latch

without requiring the operator to touch it, there is provided a trip plate, 12, hinged to the bracket, 10, below the portion, 10^c, of the slot, and adapted by gravity to fall and be held lying in the position shown in Fig. 3, entirely beyond the notch, 10^d, but having its forward edge at that position sloping up from the said notch and provided with a notch, 12^a, into which the stud, 11^a, will run upon the operator slightly lifting the lounge-back, 9, from the position at which it is held by the engagement of the stud, 11^a, in the notch, 10^d. Upon such engagement of the stud in the notch, 12^a, the operator ceasing to lift the lounge-back, and allowing the weight to rest upon the latch, 12, said latch will be tilted forward over its pivot to the position shown in Fig. 4, at which the latch masks the notch, 10^d, the lower edge of its own notch, 12^a, being at the level of the top of the notch, 10^d—that is, the level of the lower edge of the slot, 10^c—so that the stud, 11^a, passes out of the notch, 12^a, onto said sloping edge of the slot, 10^c, and the latch being thereby disengaged, runs in down the slot 10, permitting the lounge-back, 9, to be folded down to operative position without the operator having been obliged to touch the latch.

30 The lounge seat, 6, at operative position is supported by the member, 5, lodging upon brackets, 13, upon the lounge ends, and it is secured in this position by a catch, 15, upon the rear edge of the lounge seat engaging the bottom board, 8^d, of the box, 8. Preferably the said bottom board is provided with a wearing plate, 8^e, at its forward edge and lower side for engagement of the latch, 15. For releasing the latch there may be provided a flexible strap, 16, secured to the back edge of the lounge seat and running through an eye, 15^a, in the upper end of the latch, said strap being accessible when the lounge back is swung up as is necessary to swing the lounge seat upward and forward when shifting the parts to bed-supporting position. In addition to the provision described for latching the lounge seat down, it is stopped and locked at operative position by the back, 9, when the latter is swung down to operative position resting upon the forward sloping edges of the box members, 8^b, 8^c, and in that position said lounge back, 9, covers and conceals the latching device, 15, and its operating strap. It will be observed that with this construction there is provided ample room under the lounge seat and in the lower part of the back for the fixed bedding, such as a mattress which may be attached to the folding bed members, and that the box, 8, provides clear and unobstructed space not intruded into by any of the folding members or metal parts and easily accessible for keeping it perfectly clean, in which the removable parts of the bedding may be

neatly stored when the furniture is folded up to use as a lounge or seat.

In view of the form of the lounge back, 9, when upholstered, as is customary and desirable, and particularly in view of the fact of the upper edge of said back being desirably curved in vertical fore-and-aft section, as seen in Fig. 1, and in view of the desirability of avoiding exposure of metal parts adjacent to the upholstery, the hinge connection of the back at its upper edge to the lounge frame is effected by hinges of a special form, each consisting of two flexible straps, 25 and 26, which may be made in appearance to match the upholstery, having their rear end portions lapped one above and one below the top rail or board, 8^a, of the box, 8, and their forward ends lapped upon the opposite surfaces of the upper edge frame bar, 9^a, of the back, 9, the two straps crossing each other between the two rails or bars, 8^a and 9^a, the strap, 25, for example, having its rear portion lapped under the bar, 8^a, and in front of the bar, 9^a, and the other strap, 26, having its rear portion lapped on top of the bar, 8^a, and on the rear side of the bar, 9^a. This gives a hinge which is not only perfectly flexible and permits the back to swing freely through its whole range of movement, but also avoids the exposure of any metal parts adjacent to the upholstery and wood members of the structure.

It will be understood that the usual method of storing bedding in the box, 8, will be to pile up the several pieces of bedding upon the bottom, 8^d, which will thus amount to a shelf. Said bottom, 8^d, is supported so as to become an effective shelf independently of the remainder of the box, the support being afforded by the brackets, 1^x, secured to the lounge ends, 1, and to the shelf or box bottom, 8^d, said bracket being preferably under said box bottom or shelf. The box ends, 8^b, are preferably mounted so as to be directly secured to the lounge ends, 1, as shown in the drawings. Such direct securing for convenience of detaching the box is preferably made by applying plates, 1^y, lapping the rear edges of each box and the adjacent lounge end, the plate being secured by screws to both said parts. I do not limit myself to this particular expedient for securing the box ends to the respective lounge ends. A wide variety of devices and expedients obviously may be applied to this purpose.

I claim:—

1. In a folding bed lounge, in combination with a lounge frame having a rigid back portion, a lounge back hinged at its upper edge to said rigid back portion for swinging upward from operative position; a bracket and a pivoted latch, one mounted upon the frame and the other mounted upon the upfolding back, the latch running on the

- bracket as the back swings, and said bracket and latch having coöperating features for engagement to hold the back at upraised position, and a device associated with said latch and bracket and operated by lifting the back beyond engaging position for preventing reengagement upon downward movement of the back.
2. A folding bed lounge comprising a lounge frame, a folding bed frame of which one member constitutes a lounge seat support hinged at its forward edge to the lounge frame and adapted to swing upward from seat-supporting position, and forward 10 and downward to bed-supporting position, the remainder of the folding bed frame being hinged for folding under said lounge-seat-supporting member at seat-supporting position of the latter, the lounge frame comprising in fixed position at the back and upper part a forwardly open box whose lower side is behind the rear edge of the lounge-seat at said seat-supporting position, said lounge seat and lower side of the box 15 being provided with coöperating devices for latching the lounge-seat down at seat-supporting position.
3. In a folding bed lounge, in combination with a lounge frame having a rigid 20 back portion, a lounge back hinged at its upper edge to said rigid back portion for swinging upward from operative position; a bracket mounted upon the frame and a latch hinged to the upfolding back, engaging 25 and running on an edge of the bracket 30
- as the back swings the bracket having a notch at the upper part for engaging the latch to hold the back at upraised position; a trip plate pivoted to the bracket, having its edge beyond the notch provided with a 35 notch adapted to be engaged by the latch upon swinging the back up beyond the position for engaging the first-mentioned notch on the bracket, the trip plate being adapted upon such engagement to swing 40 down past the bracket notch and mask the same and release the latch.
4. In a folding bed lounge, in combination with a fixed lounge frame having in the back thereof a forwardly open box for bedding; a lounge back which forms the front cover for such box and which is hinged to the frame at its upper edge for folding upward to open the box; a device for supporting the lounge back at open position, comprising a bracket mounted in the box, and a latch hinged upon the back side of the lounge back engaging the bracket, the box having two vertical fore-and-aft partitions 45 between which the bracket is mounted and the latch plays, said partitions constituting by their forward edges a stop and support for the lounge back at closed position.
- In testimony whereof I have hereunto set my hand at Naperville, Illinois, this 20th 50 day of January, 1914.
- ADOLPH KNOSHER.
